ABSTRACT

A flushing apparatus for plumbing fixtures and the like embodies a single main moving member with flushing valve attached at the bottom and the upper end open to receive makeup or refill water to restore the trap seal in the fixture below. The main moving member also provides an overflow for flush tank water and is arranged concentrically around a fixed upright member which is secured to the tank bottom wall at its outlet. The main moving member with flushing valve attached is raised by utilizing the pressure of tank refill water and is held open by this pressure until the flush tank is empty. Accuracy of operation is assured. A float-operated valve is used to control the flow of refill water, diverting it from one passageway to another to allow the flushing valve to close. A chamber containing the valve float has its lower end extended to a point near the bottom of the tank, thus accurately timing the opening of the float valve with the emptying of the tank, and thus diverting the refill water to allow the flushing valve to close.

PATENTED AUG 26 1975

FIG. 2

FLUSHING APPARATUS

BACKGROUND OF THE INVENTION

The invention relates to improvements on the flushing apparatus disclosed in U.S. Pat. No. 3,816,856, issued to James W. Braswell on June 18, 1974. More particularly, the present invention has for its objective to improve the construction and the mode of operation of the flushing apparatus in terms of timing the opening of a float-operated valve employed to control the flow of refill water, and diverting such water from one passageway to another to allow closing of the main flushing valve. The float-operated valve is accurately timed to open in relation to the emptying of the flush tank, and this is accomplished by extending the float valve chamber downwardly to a point near the bottom wall of the tank.

Additionally, the invention employs a unique new concept for elevating the main moving member of the apparatus with the flushing valve attached. In this connection, the pressure of the refill water entering the tank is utilized, and the flushing valve is held open by this pressure until the flush tank is empty.

The construction allows complete drainage of the tank. The main moving member is free to move up and down and to rotate about the fixed upright member. The apparatus may be installed on existing tanks or may be used for new installations. Parts are provided to prevent the vortex caused by water flowing through the tank outlet.

When the flush tank is filling and refill water is diverted into the top of the main moving member to refill the fixture, air is trapped in the flow chamber and the float remains down. The air remains trapped in the chamber, opposed by water pressure at the top openings of the chamber.

When the flush tank is full, and the tank filling valve closes terminating the flow of water to the tank and to the refill tube, pressure is released at the top openings of the float chamber to allow the trapped air to escape, and the float rises as water fills the chamber rising from below. This closes the float valve that diverts refill water and it remains closed until the next flushing cycle of operation.

To initiate the flushing cycle, the flow of refill water must be started. This is done by causing the tank filling valve to open and provide the necessary volume and pressure of the refill water.

To open the tank filling valve, the pressure or force that holds this valve closed must be relieved. The method used depends on the type of filling valve in the particular installation. In the disclosed embodiment, a conventional float-operated filling valve has the usual float ball replaced with a hollow float having a bottom opening so as to trap the air therein when the tank fills with water. A tube connected into the top of this float has its other end submerged below water level to trap the air in the float. To activate the tank filling valve, the flexible tube is manually raised above water level to allow the escape of air from the float, thus sinking the float to open the filling valve. The tube end is then dropped to its lower position ready for the next operation. This movement of the flexible tube is carried out by utilizing a conventional flush tank handle and an extended lever connected to the end of the tube. If desired, the same operation may be accomplished by utilizing an air release valve of the push button type at-

tached to the end of a tube as shown in U.S. Pat. No. 2,740,129.

Other features and advantages of the present invention will become apparent during the course of the following detailed description.

BRIEF DESCRIPTION OF DRAWING FIGURES

FIG. 1 is a side elevation, partly in section, of a flush tank for plumbing fixtures equipped with the improved flushing apparatus of the invention.

FIG. 2 is an enlarged central vertical section taken through the flushing apparatus.

FIG. 3 is a horizontal cross section taken on line 3—3 of FIG. 2.

FIG. 4 is a similar section taken on line 4—4 of FIG. 2.

FIG. 5 is a similar section taken on line 5—5 of FIG. 2.

DETAILED DESCRIPTION

Referring to the drawings in detail, the illustrated flush tank has a bottom wall 1, recessed centrally at 2, to allow complete drainage of water. A threaded fitting 3 is anchored securely within tank outlet opening 3' in a conventional manner and is coupled with a mating fitting or sleeve 4 equipped with a compressible gasket 5 to prevent water leakage. Spacer elements 6 rigid with the fitting 4 are also joined to an upright vertical member or tube 7 having an enlarged upper portion 8 in the nature of a cup or cylinder and an intermediate internally threaded coupling section 9. The elements 4, 6, 7, 8 and 9 thus constitute a fixed upright structure which is anchored to the tank bottom wall 1 in the manner shown, or in any other appropriate manner which may be found desirable for a particular installation or a particular type of plumbing fixture. Preferably, the entire apparatus is installable on the flush tank and removable therefrom without the necessity for separating the tank from the fixture.

The mentioned spacer elements 6 maintain the elements 4 and 7 parallel and upright within the tank. The top of fixed tube 7 is closed by a wall 10 immediately below the threaded opening in the coupling section 9.

A further fixed vertical pipe 11 has a lower threaded end 12 engaged in threaded socket portion 9. The top of pipe 11 is joined to a right angular elbow 13 having a horizontal threaded extension 14 and a lower shoulder 15. Near its lower end, the pipe 11 has a pair of diametrically opposed orifices 16 opening into chamber 8' of cup-like portion 8 near the bottom wall of the latter.

A main moving member or sleeve 17 has an annular groove 18 near its lower end receiving and holding an elastic flushing valve element 19 adapted to sealingly engage the top flange of fitting 4 while in a down position. The sleeve 17 is coaxial and concentric with elements 7 and 8, and the upper end of the sleeve is provided with a partition wall 20 through which the sleeve 17 is joined to an interior relatively short tubular part 21. The partition wall 20 has a plurality of spaced openings 22 formed therethrough for a purpose to be described. These openings allow refill water to enter the sleeve 17 and to flow downwardly to the plumbing fixture below. The openings 22 also act as a vacuum breaker and anti-siphoning means for sanitary reasons.

The tubular portion 21 fits closely and slidably around the fixed pipe 11. At the lower end of the element 21, a horizontal annular partition 23 projects out-

wardly therefrom and has its peripheral portion in sliding contact with the bore of cup-like element 8, thus forming a piston member in the chamber 8' between pipe 11 and cup-like member 8. Several vanes 24 are provided on the bottom of the piston member and are set at an angle to orifices 16, FIG. 3. Near its upper end, the element 8 is provided with one or more vertically elongated openings 25 for a purpose to be described.

The sleeve 17 is telescoped over the internal fixed upright parts and is held properly aligned at its bottom by radial spacers 6 and at its top by the pipe 11 engaged in sleeve portion 21. The sleeve 17 is free to move up and down and to rotate and will always accurately seat flushing valve element 19 when down. The high position of sleeve 17 is indicated in broken lines at 26 in FIG. 2.

The numeral 27 designates a fitting having passageways 28 and 29. A threaded terminal 30 on one end of fitting 27 is coupled to threaded extension 14 while a right angular depending threaded terminal 31 is similarly coupled within a threaded socket 33 of a tubular body 39 forming a float chamber. A tube connection 32 on fitting 27 is coupled with a refilling tube 34 leading from a tank refilling valve 46, FIG. 1. Fitting 27 additionally has a bore or passageway 35 formed vertically therein and slidably receiving a valve stem 36 to form a guide and valve seat.

A cylindrical float 37 secured to the stem 36 or valve element is provided on its lower end with vanes 38 arranged at an angle to the flow of water for a purpose later to be described. The tubular body 39 defines a chamber 45 for the float 37 within which the latter is free to move up and down so that valve element 36 may open and close passageway 29. The lowermost position of float 37 is indicated in broken lines by the numeral 40, FIG. 2. Tubular body 39 has a lower reduced diameter extension 41 terminating near and above tank bottom wall 1 and having an angled or beveled lower end 42. An annular shoulder 43 is formed at the juncture of elements 39 and 41 to serve as a stop for the downward movement of float 37.

It should be stated that elements 17 and 41 may have their lengths varied to suit the needs of particular flush tanks and water depths desired therein. Also, where parts are in sliding contact, it is not intended that they be so closely fitted as to resist their movement. Small quantities of water escaping between such sliding members is anticipated, and an excess of water and pressure will always be available despite such seepage.

Fitting 27 is provided with a vertical orifice 44 leading downwardly from passageway 29 leading into the top of chamber 45.

Filling valve 46 is connected to fitting 27 by tube 34, as described, and to hollow float 47 in the flush tank by a valve operating rod 48. The hollow float 47 is connected to a flexible tube 49 which communicates at one end with the top of the float. At its lower end, the tube is attached to a lever 50, in turn having its upper end secured to the customary tank handle 51.

The high water level in the flush tank is shown by the numeral 52 and the overflow level by the numeral 53. Arrow 54' indicates the flow of refill water being diverted into the top of sleeve 17 and arrow 55 indicates the flow of refill water used to raise the sleeve 17 and valve 19 for the flushing operation. The flush tank itself is indicated by the numeral 54.

OPERATION

Assume that the flush tank 54 is filled with water to the high water level 52. Then manual pressure applied to the handle 51 will raise the lever 50 so that the lower end of tube 49 is raised above the water level 52. Air trapped in the float 47 is released through the tube and the float sinks with arm 48 causing filling valve 46 to open so that water will enter the tank through tube 34, passageway 28, pipe 11, orifices 16 and into the chamber 8' below piston 23. Here, the incoming water acts on the bottom of piston 23 and forces main sleeve 17 upwardly to unseat flushing valve 19. As the water flows through orifices 16, it strikes angled vanes 24 inducing slight rotation of sleeve 17 on its vertical axis, as it rises and becomes water-borne. Valve 19 will thus be seated in a different place after each flushing cycle to provide a cleaning action on the valve seat 4.

Manual pressure on handle 51 is momentary, and when removed, lever 50 and tube 49 descend to the lower position shown in FIG. 1 ready for the next flushing cycle.

At this point, chamber 45 is filled with water, and float 37 and valve element 36 are raised with passageway 29 closed, sending the refill water through passageway 28, as stated above.

When piston 23 rises, it will reach elongated opening 25 thus allowing water to escape through such opening, partially relieving the pressure. This movement is progressive, so that the piston finds a balancing point and is held in a treading mode, suspending sleeve 17 and valve 19 in the open position to complete the flushing operation.

As the tank water recedes, water is retained in chamber 45, being held by a slight vacuum, as no air is allowed to enter chamber 45. Orifice 44 connects into passageway 29 on the pressure side of valve element 36 so that only a small amount of water enters chamber 45 at this moment. Thus, valve element 36 is held closed, as shown, until the tank water is completely empty into the fixture for flushing.

With the tank empty, the lower end of tubular extension 41 is open to air and angled end 42 allows air to enter extension 41 and chamber 45 as the flush tank empties. The float 37 immediately lowers in chamber 45 causing valve element 36 to open passageway 29 for diverting refill water through passageway 29 onto the top of sleeve 17, as indicated by the arrow 54'. As water follows the path of least resistance, pressure is relieved in chamber 8' and the sleeve 17 is gradually lowered by gravity to seat flushing valve 19. Water remains in chamber 8' and seeps by piston 23 as the latter lowers with sleeve 17 to provide a gradual or retarded movement.

The tank 54 is now being filled with water and refill water is entering sleeve 17 through openings 22 and annular space 17' between elements 8 and 17. This water flows downwardly into the fixture below to restore the trap seal. As the tank water level rises, air is trapped in chamber 45, as orifice 44 opening into passageway 29 has a slight water pressure opposing the upward flow of air. This condition continues until the tank is refilled to the level 52, at which time the filling valve 46 is closed by the action of float 47, thus stopping the flow of water through the tube 34.

Water drains from passageway 29 and allows air trapped in chamber 45 to escape through port 44 and

water now rises in chamber 45, lifting float 37 and moving valve element 36 to the uppermost position closing passageway 29. As water flows from extension 41 into chamber 45, it impinges on vanes 38, and they being at an angle to the flow of water cause elements 37 and 36 to rotate slightly on their common axis to effect a cleaning action of their mating surfaces.

The apparatus is now in condition for another flushing cycle.

It is to be understood that the form of the invention herewith shown and described is to be taken as a preferred example of the same, and that various changes in the shape, size and arrangement of parts may be resorted to, without departing from the spirit of the invention or scope of the subjoined claims.

I claim:

1. A flushing apparatus for use with a flush tank having a bottom discharge opening comprising a fixed upright member anchored with respect to the discharge opening and extending thereabove and having a cup-like top portion, a vertical pipe coupled with said upright member and extending through the cup-like top portion and above the same, a fitting means coupled to said vertical pipe and having a first passageway in communication with the bore of said pipe and a second passageway leading from the first passageway and opening exteriorly of said pipe, a filling valve means coupled with said fitting means and delivering refill water to the first passageway when open, a main vertical sleeve telescoped movably over the fixed upright member and said vertical pipe, an interior sleeve part on said main vertical sleeve and telescoped over said vertical pipe and projecting into said cup-like top portion, a piston element on said interior sleeve part and engaged movably in the bore of the cup-like top portion, said cup-like top portion having a side wall opening near the top thereof and said vertical pipe having a lateral port near the bottom of the cup-like portion, a flushing valve element on the lower end of the main vertical sleeve, a tubular member coupled to the fitting means and depending therefrom and terminating near the bottom of a tank utilizing said apparatus and having a float chamber, a float body within the float chamber movably, a valve element secured to the float body and extending thereabove and projecting into a guidance and seating opening of said fitting means and adapted in a raised position to close said second passageway and in a lowered position to open the second passageway, and there being a narrow orifice interconnecting said float chamber and second passageway external to said guidance and seat opening.

2. A flushing apparatus comprising a fixed upright support and guide structure mountable in a flush tank adjacent the tank outlet, a main flushing valve movable member in telescoped engagement with said upright structure, said upright structure and said main member cooperating to form fluid flow responsive means to elevate said member with respect to said upright structure, said member responding to gravity when lowering, pressurized fluid delivery means coupled with said upright structure and having fluid passage means communicating with said fluid flow responsive means, and a float elevated gravity responsive valve device connected with said pressurized fluid delivery means and operable to divert the delivery of fluid from said fluid passage means to a second passage means delivering the fluid into a flush tank exteriorly of said member,

and said valve device including a float chamber having a passageway extending close to the bottom of a flush tank for the entry of air into the passageway and said float chamber when the tank is empty and for the entry of tank fluid when the fluid level in the tank is rising.

3. A flushing apparatus according to claim 2, and said fixed upright support and guide structure including a cup-like top portion having a side wall opening near its top, said main flushing valve movable member telescoped over the cup-like portion and having a piston body projecting into the cup-like portion and responding to the delivery of said fluid by said delivery means to elevate said member.

4. A flushing apparatus according to claim 3, and an upright pipe forming a part of said fluid delivery means coupled to said support and guide structure and disposed centrally within said cup-like portion, said piston body being tubular within the cup-like portion and being telescoped over said pipe and being joined to said member.

5. A flushing apparatus according to claim 4, and said member having a top wall joining the tubular piston body and the side wall of the member above the cup-like portion, said top wall having fluid inlet openings, said pipe having fluid outlet opening means near the bottom of the cup-like portion and below the tubular piston body.

6. A flushing apparatus according to claim 5, and an elastic annular flushing valve element secured to the lower end of the main flushing valve movable member for seating on a seat element at the bottom of a flush tank surrounding a flush tank outlet.

7. A flushing apparatus according to claim 6, and said fixed upright support and guide structure including spacer means at its lower end centering the structure relative to a tank outlet and centering and guiding said main movable member, said member telescoped over said spacer means.

8. A flushing apparatus according to claim 7, and said spacer means comprising plural radial blade-like spacer elements fixed in relationship to a center upright member, said upright member disposed inside of the main flushing valve movable member.

9. A flushing apparatus according to claim 3, and impeller vane means on said piston body in the path of said fluid entering the cup-like portion and responding to said fluid to produce turning of said main flushing valve movable member on its longitudinal axis.

10. A flushing apparatus according to claim 2, and said pressurized fluid delivery means comprising a tank refilling valve, a fitting element coupled with the fixed upright support and guide structure and coupled with said float elevated gravity responsive valve device and having divergent fluid passages, said valve device including a valve element blocking one of said passages at selected times responsive to elevation of the valve element by said float.

11. A flushing apparatus according to claim 10, and said valve device float chamber being coupled with said fitting element, said fitting element having a orifice extending between said float chamber and the fluid passage of the valve device which is blocked by said valve element.

12. A flushing apparatus according to claim 11, and said orifice being on the high pressure side of said valve element in said fitting element.

13. A flushing apparatus according to claim 12, and a tube interconnecting said fitting element to said tank refilling valve.

14. A flushing apparatus according to claim 13, and a float operated arm connected with said refilling valve to control the operation of the latter, a hollow float carried by the arm and having a fluid inlet opening, a flexible tube coupled with the hollow float at a point substantially opposite to said opening and having a free end adapted to be submerged in tank fluid and to be elevated therefrom, and a manual lever means coupled to the tube to elevate it.

15. A flushing apparatus according to claim 10, and a float body in said float chamber movably, said valve element secured directly to said float body at the top thereof, and valve element rotation inducing vane means on the bottom of the float body responding to

the entry of fluid through said float chamber passage-way.

16. A flushing apparatus according to claim 2, and said valve device comprising a substantially vertical cylinder body coupled to said fluid delivery means and extending close to the bottom of a flush tank, said cylinder body having a lower end reduced diameter tubular extension and having an upper float body chamber communicating with the bore of the extension.

17. A flushing apparatus according to claim 16, and said extension having a lower inclined terminal end.

18. A flushing apparatus according to claim 16, and there being a float body stop shoulder at the bottom of said chamber to limit downward movement of the float body.
